UNITED STATES PATENT OFFICE.

JOHN T. WILKIN, OF CONNERSVILLE, INDIANA.

DESIGN FOR A HEAD-PLATE FOR ROTARY BLOWERS.

SPECIFICATION forming part of Design No. 26,740, dated March 9, 1897.

Application filed September 24, 1896. Serial No. 606,900. Term of patent 14 years.

To all whom it may concern:

Be it known that I, JOHN T. WILKIN, a citizen of the United States, residing at Connersville, in the county of Fayette and State of Indiana, have invented and produced a new and original Design for Head-Plates for Rotary Blowers and Pumps, of which the following is a specification, reference being had to the accompanying drawing, showing a part thereof.

10 In the drawing I have illustrated my design for head-plates for rotary blowers and pumps by a general perspective view, such view being deemed necessary and adequate to fully illustrate the same.

15 The leading feature of my design consists in a head-plate A, the opposite ends of which are substantially semicircular or curved, as indicated at B, circular openings C being formed in the head-plate substantially concentric with the semicircular ends and in line with U-shaped or three-sided boxes D, which latter project from the head-plate.

20 The design further, though less essentially,

consists in a horizontal flange E, connecting the adjacent walls of the two U-shaped or three-sided boxes D; in the similarly-disposed flanges F, that connect the outer walls of the boxes with the head-plate; the vertical flange G, that connects the intermediate horizontal flange E with the head-plate; the lower horizontal base-flange H, located under the boxes D; the vertical flanges I, extending from the under sides of the boxes to the base-flange H, and, finally, in the corner-flanges J, that are located at the angles formed by the flanges F 25 and E and the side walls of the boxes D.

What I claim is—

The design for head-plates for rotary blowers, herein shown and described.

In testimony whereof I affix my signature 40 in presence of two witnesses.

JOHN T. WILKIN.
